BULB MANIPULATING DEVICE

George R. Chadsey, East Hampton, Conn.; Inez M. Davis and Ida D. Dickerson, both of Middletown, Conn., executrices of said George R. Chadsey, deceased, assignors to Chadsey Corporation, Hartford, Conn., a corporation of Connecticut

Application April 12, 1946, Serial No. 661,795

6 Claims. (Cl. 294—21)

1

This invention relates to a bulb manipulating device and especially to a device such as is particularly intended for attaching or extracting electric light bulbs from sockets in high or remote positions.

This invention is particularly adapted for use in connection with a bulb manipulating tool such as covered by my Patent No. 2,117,017, issued May 10, 1938, Tools for manipulating electric lamp bulbs.

An object of the present invention is to provide a device for use with the said tool to permit the manipulation of electric light bulbs that may be contained in sockets that are disposed in different positions and at different angles.

A further object is to provide such a device which can be quickly and easily adjusted to position the bulb engaging member at different angles and to rotate the same while in said positions.

Further objects and advantages of my invention will be more clearly understood from the following description and from the accompanying drawings in which:

Fig. 1 is an elevational side view of a device embodying my invention.

Fig. 2 is a fragmental side view, partly in central vertical section, showing the device adjusted for a different position.

Fig. 3 is a similar view showing the device adjusted for another different position.

Fig. 4 is an elevational plan view of the device as shown in Fig. 3.

Fig. 5 is an elevational plan view of the adjustable supporting member used in my device.

Fig. 6 is an elevational side view thereof.

As shown in the drawings, the numeral 5 denotes a sleeve or shell which is adapted to be mounted upon the end of a pole to permit reaching of bulbs in high positions. Upon the top of said shell, there is secured a ring gear 6 having a row of gear teeth 7 and a plurality of teeth or projections 8 for the purpose to be herein-after described.

A supporting member 9 is slidably mounted within the sleeve 5 and through the gear ring 6, and a post 10 is swivelly secured to said member by means of a pivot pin 11. The said post being permitted to swing within a notch 12 in the end of said supporting member 9 and the opposite walls of said notch being provided with oppositely disposed recesses 13, 14 and 15 to provide sockets for a hub 16 on a pinion 17 which is rotatably mounted on the post 10. The said pinion having a row of teeth 18 adapted to mesh with the teeth 7 at different angles relatively thereto for rotat-

2

ing a shank 19 which is secured to said pinion by means of a sleeve 20 providing a socket for said shank.

The said pinion is rotatably secured to the post 10 by means of a screw 21 having a tip fitting within an angular groove 22 in said post and the supporting member 9 is adjustably secured to the sleeve 5 by means of a spring operated positioning pin 23 which is normally urged into one of a series of positioning recesses 24 in said supporting member 9 for rotatably securing the member at different positions relatively to the shell 5.

In the operation of my invention, the shell 5 may be secured to the top of a suitable pole or bar which will reach the position of the bulb to be manipulated.

When it is desired to remove an electric light bulb from a socket in a high position, the bulb gripping member 25 may be placed at the proper angle, corresponding with the position of the bulb, by first loosening the screw 21 to permit raising of the pinion 17 on the post 10 so as to remove the hub 16 from the recesses in the sides of the slot 12 within which it is positioned. The member 9 is released, by pulling on the handle 26 to remove the pin 23 from the recess 24, and the member 9 may then be pulled upwardly in the shell 5 to permit the post 10 to be tilted to the angle desired and the hub 16 inserted into the corresponding recess in the sides of the slot 12.

The screw 21 is then brought into positioning engagement with the groove 22, the member 9 slid downwardly to bring the teeth of the pinion 17 into engagement with the teeth 7, and the spring pin 23 is permitted to enter the recess registering therewith to secure the said member in position.

After the device has been adjusted for the proper angle in the manner above described, it may be raised to permit engagement of the gripping member 25 with the bulb and the bulb may then be rotated in its socket by simply rotating the pole. This will in turn rotate the sleeve 5 and the gear 6 will rotate the pinion 17 on the post 10 and thus rotate the member 25 to either screw the bulb into the socket or unscrew the same from said socket.

It will be noted that the hub 16, fitting within the recesses in the edges of the slot 12, will position the holder 19 at the proper angle and permit rotation thereof with said hub rotating within the recesses; moreover positioning of the member 9 by the spring held pin 23 will retain the pinion in mesh with the ring gear 6.

It will also be noted that the angle of the shank

19 may quickly be changed by simple manipulation of the screw 21 and the pin 23. As it will be seen from the drawings, the shank 19 may, relatively to the pole, be positioned diagonally, as shown in Fig. 2, by inserting the hub 16 in the recess 15. It may be positioned perpendicularly, as shown in Fig. 1, by inserting the said hub in the recess 14, or it may be positioned straight with the pole, as shown in Fig. 3, by inserting the hub in the recess 13. When in this straight position, the teeth 18 on the pinion 17 will be in engagement with the teeth 8 and thereby prevent rotation of the pinion and shank 19 relatively to the support 9 and shell 6 so that the said shank may be rotated directly with the support 5 and the pole connected thereto.

The gripper 25 may be reversed upon the shank 19 to permit use of the tapered end 27 when needed for such as the extraction of the shell of a broken bulb.

I claim:

1. A bulb manipulating tool of the character described comprising a support, a shank rotatably mounted on the support, a gear secured to the support, a member adjustable in said support, means swivelly carried by said member for positioning the shank at different angles relatively to the support, and cooperating gear means on the support and shank for rotating the shank through rotation of the support.

2. A bulb manipulating tool of the character described comprising a support, a member slidably in said support and adapted to be positioned therein for rotation relatively to the support, a post swivelly secured to said member, a shank rotatable on said post, means for positioning said shank at different angles relatively to the support, a gear member surrounding said support, and a pinion on said shank engageable with said gear at different angles relatively thereto for rotating the shank through rotation of the support.

3. A device of the character described comprising a support including a shell having a member slidable therein, means in said shell for adjustably positioning said member, a post swivelly secured within a slot in the top of said member, a pinion slidably and rotatably mounted on said post, a hub on said pinion adapted to fit within recesses at different positions in the sides of said slot for retaining said shank at different angles relatively to said support, and a ring gear on said support for engaging the teeth of the pinion to permit rotation of the shank through rotation of the support.

4. A device of the character described comprising a support, a member slidably adjustable in said support, a post swivelly mounted in said

member, a pinion rotatable on said post, a socket on said pinion, a shank detachably secured in said socket, a gripper detachably secured on said shank, means for adjustably positioning said post and socket thereon at different angles relatively to said support, and a gear on said support engageable with said pinion when in different positions for rotating said shank by rotation of the said support.

5. A bulb manipulating tool of the character described comprising a support, a member slidably in said support and adapted to be positioned therein for rotation relatively to the support, a post swivelly and adjustably secured to said member, a shank rotatable on said post, means for positioning said shank at different angles relatively to the said member, a gear member surrounding said support, a pinion on said shank engageable with said gear member at different angles relatively thereto for rotating the shank through rotation of the support, and interengaging means on said pinion and support for securing the shank to the support against relative rotation when the said shank is positioned coaxially with said support.

10. A bulb manipulating tool of the character described comprising a support, a member slidably in said support and adapted to be positioned therein for rotation relatively to the support, the said member having a slot therein including a plurality of positioning recesses in the walls of said slot, a post swivelly secured to said member, a pinion rotatable on said post, a hub on said pinion adapted to selectively fit within said recesses for positioning the pinion at different angles, relatively to the support, a gear member surrounding said support and interengageable with said pinion for rotating the pinion on the post, the said pinion being slidable on said post to permit movement of said hub into different recesses for positioning the pinion at different angles, and means including teeth projecting inwardly from said gear and interchangeable with teeth on said pinion, when the pinion is positioned co-axially with the support, to secure the pinion to the support and against relative rotation.
